UNITED STATES PATENT OFFICE.

JOHN H. BRADNACK, OF NEW HAVEN, CONNECTICUT, ASSIGNOR TO THE TUBULAR PRODUCTS COMPANY, OF SOUTHLINGTON, CONNECTICUT, A CORPORATION.

DESIGN FOR A SMOKER'S STAND.

Application filed October 7, 1926. Serial No. 19,267. Term of patent 14 years.

To all whom it may concern:

Be it known that I, JOHN H. BRADNACK, a citizen of the United States, residing at New Haven, in the county of New Haven and State of Connecticut, have invented a new, original, and ornamental Design for a Smoker's Stand, of which the following is a specification, reference being had to the accompanying drawing, forming part thereof.

In the said drawing:—

The figure is a perspective view of a smoker's stand, showing my new design.

I claim:—

The ornamental design for a smoker's stand, as shown.

JOHN H. BRADNACK.
